UNITED STATES PATENT OFFICE.

HENRY W. WATSON, OF MITCHELLSBURG, KENTUCKY.

DESIGN FOR A WINDOW-CATCH.

SPECIFICATION forming part of Design No. 20,810, dated June 2, 1891.

Application filed May 7, 1891. Serial No. 391,951. Term of patent 7 years.

To all whom it may concern:

Be it known that I, HENRY W. WATSON, a citizen of the United States of America, and a resident of Mitchellsburg, Boyle county, in the State of Kentucky, have invented and produced a new and original Design for a Catch for Windows, &c., of which the following is a specification.

Figures 1 and 2 of the accompanying drawings, forming part of this specification, represent perspective views showing the respective sides of a catch having the peculiar shape or configuration which constitutes my design.

The leading features of this design are a hatchet-shaped or triangular portion and a relatively large circular portion at the respective extremities of a body of bell-crank shape. Said triangular portion is shown at *a*, a portion of one side being defined by a dotted line. Said circular portion is shown at *b*, and the extremities of said body of bell-crank shape, which merge into the upper side of said triangular portion at a short distance from its vertical side as viewed in the figure and into

one edge of said circular portion in line with its horizontal diameter, are shown, respectively, at *c* and *d*. Another circular portion at the angle of said body of bell-crank shape is represented at *e*, countersinks in its respective sides are represented at *f* and *g* in the respective figures, and a central hole therein is represented at *h*. Said circular portions *b* and *e* are preferably three times as thick as said triangular portion *a* and said portions *c* and *d*, and said vertical side of said triangular portion *a* is tangential to said circular portion *e*.

Having thus set forth my said design, I claim and desire to patent under this specification—

The design for a catch, substantially as shown and described.

Signed at Mitchellsburg this 14th day of April, 1891.

HENRY W. WATSON.
